UNITED STATES PATENT OFFICE

98,852

DESIGN FOR AN INSECT EXTERMINATOR

Claude E. Canning, Wilmette, Ill., assignor to
C. E. Canning, Incorporated, Chicago, Ill., a
corporation of Illinois

Application November 13, 1935, Serial No. 59,526

Term of patent 7 years

To all whom it may concern:

Be it known that I, Claude E. Canning, a citizen of the United States, residing at Wilmette, in the county of Cook and State of Illinois, have invented a new, original, and ornamental Design for an Insect Exterminator, of which the following is a specification, reference being had to the accompanying drawing, forming part thereof.

Figure 1 is a perspective view of an insect exterminator embodying my new design.

Fig. 2 is an end elevational view thereof.

My new design is characterized by a supporting casing element which is located at one side of substantially the central point of an elongated, generally cylindrical arrangement of insect exterminating elements.

I claim:

The ornamental design for an insect exterminator, substantially as shown and described.

CLAUDE E. CANNING.
